UNITED STATES PATENT OFFICE.

NATHAN A. EUBANK, OF NASHVILLE, TENNESSEE.

TIRE-RIM TOOL.

1,422,948.

Specification of Letters Patent. Patented July 18, 1922.

Application filed October 30, 1920. Serial No. 420,723.

To all whom it may concern:

Be it known that I, NATHAN A. EUBANK, a citizen of the United States, residing at Nashville, in the county of Davidson and State of Tennessee, have invented new and useful Improvements in Tire-Rim Tools, of which the following is a specification.

This invention relates to tools designed for use in connection with pneumatic tire rims which are split so that they may be contracted and expanded for ready removal and replacement of the tire.

The invention has for its object to provide a very efficient tool for contracting and expanding a rim of the kind stated, and also one which is easy to operate, and strong and durable in construction.

The objects stated are attained by means of a novel combination and arrangement of parts to be hereinafter described and claimed, and in order that the same may be better understood, reference is had to the accompanying drawings forming a part of this specification.

In the drawings—

Figure 1 is a side elevation of the tool; Fig. 2 is a plan view thereof; Fig. 3 is a cross-section on the line 3—3 of Fig. 2; Fig. 4 is front elevation of one of the rim-engaging hooks, partly broken away, Fig. 5 is a side elevation of said hook, and Fig. 6 is a detail showing a slight modification.

Referring specifically to the drawings 10 which is provided with legs 11 extending downwardly from its under side for supporting the device in proper operative position on the ground or on any other supporting surface, the base plate being held spaced 40 from the latter by the legs.

The base plate 10 has a large central opening 12 and radiating from the latter are three grooves 13 made in the top of the plate and extending to the edge or periphery 45 thereof. In each one of these grooves is slidably mounted an arm 14 of such length that its outer end is positioned outside the periphery of the base plate, and said arm having its outer end provided with a down-turned hook 15. These arms extend radially with respect to the center of the base plate, and they are spaced equal distances from each other. In order to prevent upward displacement of the arms they are 55 dovetail-shaped in cross-section, the grooves

in which they slidably seat being correspondingly shaped.

The inner ends of the arms 14 project into the plane of the opening 12 in the base plate 10, and over said opening is mounted 60 a rotatable disk 16 which is held down on the base plate, and over the arms, by clips 17 carried by the base plate and overhanging the disk at its periphery. From the center of the disk rises a stem 18 for the 65 application of a suitable tool for rotating the disk, said tool being a socket wrench 19 having an operating handle 19^a and carrying a spring-actuated latch pin 20 passing into the socket to enter a keeper aperture 21 70 in the stem 18, and thus lock the wrench to said stem.

The under side of the disk 16 has a spirally arranged groove 22 and the arms 14 have teeth 23 on top which seat in said groove. 75 It will therefore be seen that the arms are uniformly advanced or retracted when the disk is rotated, the rotation of the disk in one direction advancing the arms, and its rotation in the opposite direction retracting 80 the arms, the movement of the latter being radial with respect to the center of the device.

When the device is used for contracting a tire rim 24 for removal of the tire therefrom, the rim is placed to encircle the device and the arms 14 are adjusted to engage their hooks 15 over the rim edge. The disk 16 is now rotated to draw in or retract the arms 14, whereupon the rim is contracted by 90 the ends at the split portion thereof being pulled inwardly until they overlap. To expand the rim, the arms 14 are adjusted to position their outer ends against the inner surface of the rim, and then upon operating 95 the disk 16 to advance the arms outwardly the rim is expanded in an obvious manner to bring its ends together at the split portion.

It will be noted that two adjacent arms 14 are fitted at their outer ends with rollers 25 to bear against the rim 24 when it is being expanded as hereinbefore described, thereby reducing friction to a minimum. The rim is placed so that the rollers 25 engage it on 100 opposite sides of the split where the greatest movement of the rim occurs when it is being expanded to its true circular contour, the two ends of the rim here then also moving laterally in opposite direction. The arm 110

14 which is not fitted with a roller is positioned diametrically opposite the split where there is no side or lateral movement of the rim while it is being expanded.

5 The lateral movement of the two ends of the rim 24 hereinbefore mentioned also takes place when the rim is being contracted, the two ends now moving toward each other so as to finally assume an overlapping position, 10 and for this reason two of the hooks 15 are provided with pivoted terminals or points 26, the rim being placed so that these two hooks engage the rim on opposite sides of its split. The terminals 26 are pivoted, as 15 shown at 27 to swing laterally and thus follow the lateral movement of the rim ends. The hooks carrying the pivoted terminals 26 have slots 28 in their ends to seat the inner ends of said terminal portions, and the inner 20 ends of the latter are beveled on opposite sides to abut against the inner end walls of the slots so as to limit the lateral swing and thus prevent said terminal portions from swinging laterally too far and thus slipping 25 off the rim.

All the parts of the device are made of metal, and hence it is strong and durable, and by its use the operation of expanding or contracting a tire rim for the purpose stated 30 is easily and quickly effected.

Fig. 6 shows a slightly different shaped base plate 10^a, the same being substantially triangular instead of circular, the purpose of this shape being to reduce the weight of the tool.

35

I claim:

1. A tire-rim tool comprising a base, radially movable arms carried by the base and having rim-engaging surfaces and depending hooks at their outer ends, the hooks of 40 two adjacent arms having points which are pivoted to swing laterally, a rotatable spirally grooved member mounted on the base over the arms, said arms having teeth seating in the grooves of said member, and means 45 for rotating the grooved member.

2. A tire-rim tool comprising a base, radially movable arms carried by the base and having rim-engaging surfaces and depending hooks at their outer ends, the hooks of 50 two adjacent arms having points which are pivoted to swing laterally, means for limiting such swing, a rotatable spirally grooved member mounted on the base over the arms, said arms having teeth seating in the grooves 55 of said member, and means for rotating the grooved member.

October 2, 1920.

NATHAN A. EUBANK.
